UNITED STATES PATENT OFFICE

GEORGE D. PARKER, OF RIVERSIDE, CALIFORNIA; CLARA B. PARKER EXECUTRIX OF
WILL OF SAID GEORGE D. PARKER, DECEASED

APPARATUS FOR WELL DRILLING

Application filed August 18, 1923. Serial No. 658,152.

This invention relates to a method and apparatus for drilling wells and particularly for drilling oil wells.

The method in use at the present time for drilling oil wells, and the apparatus also, is of such a nature that more or less difficulty is continually encountered in properly controlling the drilling operations and implements so as to prevent quite frequent breakage that almost invariably occurs when the drill encounters hard strata while running at full speed, under full engine power and high steam pressure.

If the operators were always conscientious and watched the action of the machinery carefully, and fed the drills carefully into the formation, the breakages would not be so frequent. I have found that many times the drill is forced beyond its endurance and purposely broken so the crew may disport themselves as they wish while a few "fish" for the broken drill, which operation may be manipulated in such a manner as to be unduly prolonged, or it may be that they never get the broken part out of the hole, in which case that particular hole must be abandoned as they cannot proceed with the drilling with part of a broken drill blocking the way.

I have also found that a tacit understanding exists among drilling crews whereby more or less time is wasted by letting their drills "circulate," as they call it. This particular procedure contemplates lowering the drill part way into the hole but not to the bottom, and while thus suspended in space, the drilling machinery is set into slow motion and thus run idle for quite long periods of time. The crew meantime going away on missions of pleasure. This practice is particularly true of the night crews, who occupy the time in sleep.

At stated periods a general report is made covering all of the drill crews belonging to one rig and in making up this report the total footage of all the crews of the rig is added up and divided by the number of crews operating, this latter amount, slightly juggled perhaps so that all will not be exactly the same, is then credited to the several crews so that the report indicates that

each crew has been working as per schedule and no evidence is available to show otherwise.

One of the objects of my invention is to provide a method and apparatus whereby the whole operation of drilling may be controlled by either manually, or automatically controlled operating devices, in such manner that only sufficient power may be applied to operate the drill under normal conditions, and which will compel the operator to use the necessary caution in the manipulation of the apparatus to prevent breakages.

These control means will permit the transmission mechanism to slip when undue resistance is encountered by the drill and will practically eliminate breakage from this cause.

Another object of the invention resides in so connecting and correlating the several control means that the operator may manipulate the apparatus through manual controls where the nature of the work will permit, or where it may seem more desirable to do it this way, and to immediately utilize the automatic controls where that means seems preferable. Changing from one to the other at will may be preferable while drilling through strata of differing resistance.

The automatic control means under certain conditions of operation will be found preferable to the manual control on account of its sensitiveness to variations in resistance met by the point of the drill.

The maximum torque load that any drill shank of given cross section will sustain may easily be determined, and after once ascertained the automatic control means may be adjusted to operate at any point before this maximum torque load is reached and thus relieve the strain on the mechanism and permit the drill to encounter this increased torque gradually, even to the point of reversing the operative means and thus lift the drill slightly from the work, thus immediately reducing the resistance when the mechanism will at once return the drill to the work and permit it to take a new bite and gradually work its way through the obstruction. This method of operation becomes

particularly desirable where a new and sharp drill is being used, the sharp teeth biting more quickly and deeper than after they become somewhat worn.

5 Another object of the invention resides in providing automatic recording means whereby a time chart will indicate and automatically record the amount of power utilized in the apparatus over fixed periods of time, for example over periods of twenty four hours. This automatic recording device to be connected with and operable by the power medium being used, which may be steam, air, electricity or any other medium suitable for 10 the purpose. This indicator would show a minimum or no consumption of power if the apparatus was run idle, while if worked to the maximum of its ability would show the maximum consumption of power. Likewise 15 during ordinary operations where the drill is continually meeting and overcoming varying resistance, the power consumption will vary with the resistance with the result that the chart line over the period, will show 20 peak loads all along its course and will give a very accurate and intelligible record of this work period. This record will be produced automatically and will be contained in a sealed compartment, available only to 25 such person or persons as are interested in getting the maximum amount of work out of the crews and rigs. Under this method of 30 charting the operations of a drill outfit every phase and variation of power consumption 35 will be indicated and thus enable the inspector or superintendent of the outfit to know just what each crew has accomplished during their shift, and to intelligently compare the work of the several crews. If a 40 crew circulated their drill and thus neglected their work the chart would show a period of uniform power flow of a minimum pressure and immediately indicate to the inspector that such circulation had been indulged in. 45 He would know that drilling could not be accomplished with so low a power consumption. On the other hand, a comparison of the chart lines with the actual depth of holes drilled over the chart periods, by the different crews would indicate whether the 50 lines were produced by the drill actually going through strata or whether the chart was produced through fraudulent manipulation of the apparatus to make it appear that 55 actual work had been done. It appears therefore that the foregoing method of indicating and recording work done with apparatus of this type, marks an important step of advance in the art.

60 In addition to the recording indicator I will place a visual indicator in such a position that the operator may at all times know exactly the pressure he is employing to do the work. This indicator will have points of 65 normal operation and danger point indicat-

ed as well as a movable hand indicating the actual pressure being employed at every instant. This will enable the operator to watch his work and the instant the movable hand indicates a sudden increase in pressure due to the drill encountering added resistance he will immediately ease off on the feed of the drill into the formation and thus give it a chance to work its way gradually through the material. By means of 70 watching this indicator and manipulating his operative devices accordingly he will be able to overcome most any condition without the danger of breakage or disablement of the machinery.

75 Another object of the invention resides in providing a reduction gear arrangement of quite a high gear ratio, for raising and lowering the drill, which reduction gear may be manipulated manually or automatically as may be desired. Means are provided whereby the operator may instantly apply either the manual or the automatic control to the operation in hand. Suitable levers 80 and other manipulative devices are carried to positions of most convenient accessibility.

85 With such objects in view as well as other advantages inherent in the invention, the novel structure peculiarities, novel organization of elements, and the separate and collective operations involved in carrying out the recited objects of my invention, which will be made the subject matter of claims 90 hereto appended, I wish it understood that the several necessary elements and combinations constituting the same may be varied in their proportions, placement and general arrangement without departing from the scope 95 and nature of my invention.

100 In carrying out the objects of my invention in a concrete form or machine, further objects, advantages and improvements have been evolved than have been recited, and in order to make the invention more clearly 105 understood there are shown, somewhat diagrammatically, in the accompanying drawings means and mechanism embodying the preferred structural arrangement and the preferred disposition of the different parts 110 and combinations, without limiting my claims to the details of construction shown, in which I have simply illustrated one way of embodying the creative part or conception of the invention in a concrete form of machine or apparatus. The described devices are simply embodiments of the invention which other structures might also employ and some of 115 the parts or combinations of parts may be used without the others in different types of such apparatus without departure from the purview of my invention and I regard myself as entitled to such variations from 120 the shown and described devices as fall with- 125 130

in the scope and meaning of the claims here-to appended.

In connection with the drawings illustrating my invention forming a part of this specification I wish to further point out that the general arrangement of the related parts, their placement and operative timing have been so shown and displayed that a clear and comprehensive understanding of the invention may be had. In order to do this most effectively it seemed desirable to show the various parts and operative elements in somewhat diagrammatic form and omit from the drawings all of the apparatus connected with the bailing of sand and water out of the hole and for lowering and placing the casings, showing only such parts and elements that have a bearing on the drilling operations.

Throughout this specification I will refer to steam as a power medium. I do this on account of the very general use of this element, but wish it understood that any other power medium is applicable to a practice and use of my improved method and apparatus. For example, electricity is a very generally used power medium and may be used to operate drilling and drill control mechanism in practically the same manner as steam or any other flexible medium.

Referring now to the drawings forming a part of this specification in which like figures of reference indicate like parts in the several views.

Figure 1 represents a plan of an apparatus embodying my invention. In this view the drilling implement is shown as connected by the several clutches to the main source of power, here indicated as a steam engine, while the drill lowering and raising windlass and attending mechanism is shown disconnected from the main power source and is thus controllable by means of the manual control devices or the automatic control devices. Only a part of the tower is shown.

Figure 2 is a vertical elevation looking in the direction of the arrows 2-2 of Figure 1 showing the arrangement and placement of the various parts and elements constituting the manual and automatic control devices for raising and lowering the drilling implement into the formation. This view shows only the parts connected with this assemblage; the parts of the apparatus lying beyond have been omitted to avoid confusion.

Figure 3 is a side elevation of the apparatus as shown in Fig. 1 with the various parts and operative elements in practically the same positions as Fig. 1. This view shows some additional parts of the tower to better illustrate a way of mounting the various instruments and elements attending the operation of the apparatus.

Fig. 4 is an enlarged view of the steam pressure gauge illustrating how the normal and danger signal hands would be arranged

and the working indicator hand which advises the operator of the pressure being employed at all times.

Fig. 5 is an enlarged view of the recording indicator which is normally a sealed compartment with or without a visual opening; I have shown it with a visual opening.

Fig. 6 is a partial sectional elevation of the friction driven gear that turns the drill and is taken on line 6-6 of Fig. 1.

The numeral 1 indicates a tower of ordinary construction in its entirety. The tower of Fig. 1 is broken away and some parts omitted from this figure are shown in Figure 3 so that its showing in these two views will not coincide in all particulars. 2 represents a steam engine of the ordinary type used for drilling purposes. 3 represents the main steam line conveying steam to the engine and other parts of the apparatus where steam is employed. 4 represents an ordinary reducing valve by means of which the steam pressure may be regulated to any pressure desired and thus confine the operations to that pressure which may be low enough to prevent breakage of the drill or any other part of the mechanism. This device used without any of the other appliances would have a very great tendency to eliminate many of the troubles now encountered in using unlimited pressure. With this device alone the operator would be unable to force the drilling implement beyond its endurance; when it struck sufficient resistance it would simply stop all of the machinery and the operator would have to lift it away from the resistance and give it a new start and by handling it carefully would be able to get it going again without trouble. 5 represents a by-pass line and 6 and 7 indicate valves by means of which the reducing valve may be cut out entirely and the steam admitted to the engine without control as to pressure. This is to overcome instances where the reduced pressure will not meet conditions and it may be desirable to have more pressure available for temporary use. 8 represents a throttle valve for admitting steam to the engine in measured quantities, this valve is controlled from the operator's position by means of a bevel gear and pinion being manipulated through a rod extending to the operator's position and terminating in a hand wheel 9. A shunt pipe line 10 runs from the main steam line and distributes steam under pressure to the visual steam pressure gauge 11, the recording indicator 12, the automatic control cylinder 13 and the drill raising and lowering engine 14.

The engine 2 is of the reversing type and delivers its power to a countershaft 15 through a suitable chain and sprockets 16. The countershaft 15 carries near one end the drill rotating sprockets and chain 17, controlled by the clutch 18. On this same end

of the countershaft is located the main power drill lowering mechanism including the sprocket and chain 19, the controlling movement is accomplished with the clutch 20 controlled in the usual manner through a manually-operable lever 20'. The other end of the countershaft 15 carries another sprocket and chain 21 having the usual clutch-controlling connection 21' with the winding drum. 10 This chain 21 is operated by reversing the engine and is utilized as the main power drill raising mechanism. These mechanisms are utilized only when the drill is raised and lowered long distances, the slight raising and lowering incident to the actual drilling operation is generally accomplished with the reduction gear arrangement through either manual or power control.

The winding drum for raising and lowering the drill is indicated by the numeral 22 being equipped on either end with suitable brake drums 22' and carrying around its central portion the cable 23 which is directly connected with the drilling implement.

25 On one end of the winding drum is secured the large gear 24 meshing with the driving pinion 25.

My improved method of control of the drill during the actual drilling operations 30 is centered about the mechanism now to be described. A rocking bracket 26 is pivotally mounted at 27 and is controlled in its movements by the foot operated pedal 28; when the pedal is in the position of that shown in

35 Fig. 3 the gear 24 and pinion 25 are in operative mesh. When the pedal is placed in the opposite position the gear 24 and pinion 25 would be disconnected and the winding drum would be free to rotate of its own accord or through the gravity pull of the drilling implement. Mounted on the swinging bracket 26 is an ordinary reduction gear housing 29, having a gear 30 secured to its outer face having a handle 30' for manual operation when desired.

40 The inner face of the reduction gear casing 29 carries a locking ratchet and pawl 31 which will prevent the sudden dropping of the drill when it is being manipulated by hand, the pawl being fixedly mounted on the bracket 26. The bracket 26 is held firmly in operative position as in Figs.

45 1 and 2 by means of the toggle link 32. Mounted on the upper end of the bracket 26 is a reversing engine of usual type indicated by the numeral 14, carrying a pinion 33 meshing with the reduction gear 30. This engine receives power through the system of piping as previously described. The reversing lever 34 has two connections, one a

50 power controlled connection and the other a gravity controlled connection indicated respectively by the numerals 35 and 36. The power controlled connection terminates in a plunger riding in the control cylinder 13, 65 and the gravity connection terminates in the

weight 37. A valve 38 controls the admission of steam to the cylinder 13 whereby said cylinder may be cut out of operation if desired.

The mechanism that actually turns the 70 drill is comprised of a friction controlled gear 39 and its companion pinion 40. The construction of this friction control is illustrated in detail in Fig. 6, where it will be noted that a central sleeve 41 terminates in 75 a cupped head 42, freely rotatable on this sleeve 41 is the gear 39. Directly over the gear 39 is another cupped disk 43 preferably secured to the sleeve 41. Friction washers 44 are interposed between the disk 43, the head 42 and the web faces of the gear 39 and are held in frictional relation by means of the adjusting screws 45 carried by the fixed plate 46. This manner of friction drive is provided as an additional safety device and 80 may be set to relieve the drill at such times as sudden resistance is encountered when the operator or the automatic mechanism would not be quick enough to offer relief. It should be adjusted to relieve the drill just before the 85 maximum torque is reached which will prevent the drill from being broken. The drill implement is indicated by the numeral 47.

The carrying out of my improved method would result in approximately the following 90 operative procedure.

In describing the operation we will assume that we are dealing with a rig that is working on a partially drilled hole.

The main operator is located at approximately 100 the point indicated by the circle "A" on Fig. 1. In this position he has easy access to all of the control levers, the throttle of the main steam engine and the manually and automatically controlled devices for 105 handling the drill during the drilling operation. We will assume first that the only control device in the entire apparatus is the reducing valve 4 in the main steam line and that this valve is adjusted to admit just 110 sufficient pressure to operate the drill under ordinary drilling conditions. This being the case we will assume that the drill meets resistance that the operating pressure cannot overcome. The only recourse left to the operator is to raise the drill from the working 115 contact and relieve the resistance when the limited power will immediately start it to rotating again when the operator will lower it to the work and by careful manipulation 120 he will be able to overcome the resistance and continue with the drilling.

If a time comes when the pressure admitted by the reducing valve is not sufficient to overcome the resistance then he must cut out the 125 reducing valve temporarily and use the full steam pressure until the resistance is overcome when he will revert back to operating with the reducing valve furnishing the steam. This plan will very materially reduce the 130

breakages due to too high a steam pressure and too much power applied without due caution but is limited in its application to the times when the set pressure cannot do the work. The reducing valve is desirable at all 5 times and with all methods of operation but used in connection with the other appliances provided its action is the more effective.

We will now suppose that the reducing 10 valve is still utilized as just described but in order to safely use a higher steam pressure and still insure safety from breakage we will incorporate in the mechanism the friction driven gear mechanism as is illustrated in 15 Fig. 6. This will enable us to apply a steam pressure sufficient to overcome any ordinary resistance met by the drill and we will set the friction on the driving gear to just slip before the maximum torque load of the drill is 20 reached. Almost any time such a load is reached it comes suddenly and unless relief is immediate the drill will break, this friction drive will act as a safety element in the drilling mechanism and will surely protect the 25 drill under the extreme conditions of operation. It is easily seen that a somewhat more efficient control is thus provided. In fact, the reducing valve can safely be eliminated if the friction drive is always in line, the two 30 together however, will give a somewhat more elastic drive.

With these two devices in place we will now incorporate in the system of control another device that will be a combined manual and automatic drill feed control that will be so sensitive in its operation that every phase and variation of resistance met by the drill will be 35 instantly transmitted to this control device and the feed of the drill into the formation eased and fondled until the resistance is gradually overcome without the least bit of danger of breakage or disruption of the mechanism, except in such cases where the drill meets resistance that causes instant stoppage, when 40 the friction gear mechanism will instantly take care of it.

This combined manual and automatic control device for the feeding of the drill into the formation comprises the mechanism of Fig. 2. 45 The reduction gear mechanism 29 may be of any desired type or construction and may be of any ratio to fit it for the particular work in hand. The greater the ratio the easier it may be manually manipulated, while the lesser the 50 ratio the more sensitive it will be under the automatic control, therefore a ratio will be adopted that will adapt it to both methods of control. In the operation of this combined control device the operator will probably start 55 with the hand feature and slowly lower the drill into the formation and as soon as it has taken hold he will connect the automatic and let it take care of itself. From now on the 60 following things may happen.

65 Suppose everything is working smoothly

and suddenly the drill meets unexpected resistance, but not of sufficient extent to cause the friction gear 39 to slip. This immediate resistance will call for more steam pressure which will be immediately available on account of the sudden slowing down of the mechanism this in turn will admit more pressure behind the piston in the cylinder 13 and cause it to move forward against the gravitational pull of the weight 37 which is holding the drill to its work. This movement of the piston will in turn move the reversing lever 34 toward the reverse side of the engine 14 and ease up on the down feed of the drill; if this does not relieve the situation a continued movement of the piston in the cylinder 13 will reverse the engine 14 and the drill will be slightly lifted from working contact when it will immediately reach its normal rotative speed and on account of being relieved from the resistance the power required to rotate it will be correspondingly decreased causing a reduction in the steam pressure which will immediately permit the weight 37 to overcome the pressure back of the piston in the cylinder 13 and again lower the drill to its work. If the resistance persists and the drill is still unable to get through it the same operation just described will be repeated, the drill will be raised and lowered alternately until such time as the resistance is overcome when matters will proceed in the ordinary normal manner. This operation will continue indefinitely so long as steam is supplied to the operation of the mechanism.

If at any time the operator desires to manipulate the control device by hand while the steam is on he has only to open the stop cock 13' in the bottom of the cylinder 13 and close the valve 38 when the piston will reciprocate without resistance and he may do whatever he wishes with the control.

Whenever it is necessary to lift the drilling implement entirely out of the hole, the foot pedal 28 is operated to disconnect the gear 24 and the pinion 25 when the regular power mechanism will do the lifting through the medium of the sprocket and chain drive 21 and the clutch on this end of the windlass drum. When it comes time to again lower the drill into the hole both the clutches on the drum shaft will be disconnected and the drill will be permitted to fall by gravity but controlled by means of the brake lever 48 actuating the brake bands on each end of the winding drum. The operator will know when he has reached near the bottom when he will brake the drum, throw into engagement the gear 24 and pinion 25 and complete the lowering of the drill by means of manually operating the reduction gear device 29. From now on the operation will be continued as has been described.

The reduction gear mechanism 29 that I refer to in connection with the control of the

feeding of the drill to the formation, may be of the planetary type, or of any other type that will give sufficient ratio to suit it to this kind of duty.

5 When the operator is manipulating the reduction gear control by hand his whole attention will be directed to the steam gauge 11 which will at all times indicate to him just the amount of power and pressure he is admitting to the mechanism. The pressure hand will be moving constantly with the varying power and it will be his duty to maintain it near the location of the normal indicating hand, which location may be adjusted to suit any conditions of operation. 10 The meeting of a sudden resistance will cause the pressure hand to immediately run up toward the danger line, assuming for the time being that we are operating without the friction gear 39, the connection here being fixed, as the hand approaches the danger lines the operator turns the reduction gear arrangement to slightly raise the drill from its work and relieve the resistance, immediately lowering it again and so manipulating it until 15 the resistance is overcome. With the friction gear 39 in use the danger of too much pressure applied suddenly is not serious as the gear will slip when this occurs. 20

25 The recording indicator may have a visual opening so anyone can see the chart line as it is being produced or it may be sealed against visual inspection except by those who have a right to inspect it. The record slip is provided with suitable ruling to indicate the time of year, day of month and the hours of the period covered, it is moved by clock works in proper time and has an inking or perforating indicating pointer that will inscribe a line on the strip corresponding to the varying pressure employed during the period covered by the chart. These charts will tell a 30 very interesting story. Every variation of power will be indicated by the irregular line placed there by the ever moving indicating finger. The ruling of the chart as shown is not nearly as fine as will be used. The hour intervals should be quite extended so that every few minutes varying pressure would 35 show a bend in the chart line. A comparison of charts from the rigs forming a set under the same supervision will indicate those that are operating consistently and those that may be triflers. The shape of the chart line in 40 comparison with the footage produced by the different towers will also indicate what is being done by the various crews. 45

50 It is understood that the various arrows on the several views indicate the directions of movement without further reference thereto.

55 It is believed that the foregoing description of the method and apparatus and the operation of the same covers all of the essential features connected with such operation, 60 and while there may be more points that

could be specifically referred to they are of minor importance and will readily occur to anyone skilled in the art.

What I claim as new and desire to secure by Letters Patent is:—

70

1. An apparatus for drilling wells comprising a source of power, a transmission mechanism including a friction power transmitting element, separate motive means for controlling the operative position of said drilling implement, said power means being operable through resistance met by said drilling implement. 75

80

2. An apparatus for drilling wells comprising transmission mechanism and a drilling implement, a flexible medium for imparting movement to said transmission mechanism and drilling implement, separate power means for driving motion from said flexible medium, and for controlling the operative position of said drilling implement, the flow of said flexible medium to said separate power means being determined by the resistance met by said drilling implement. 85

90

3. An apparatus for drilling wells comprising a source of power, a transmission mechanism and a drilling implement, power means for controlling the operative position of said drilling implement including a reversible power element, gravity means for controlling one direction of movement of said power element and pressure means for controlling the other direction of movement of said power element. 95

100

4. A drill control, comprising a fluid pressure motor for raising and lowering the drill, a plunger to be operated by such fluid pressure under abnormal drill resistance to decrease the motor speed, and a weight-operated connection for restoring the motor to 105 normal speed on release of plunger pressure.

105

5. A controlling device for a drum of a drilling machine comprising driving mechanism driven by an engine and adapted to drive said drum; and a piston and cylinder 110 responsive to the pressure of the operating medium of the engine for operating and controlling said driving mechanism.

110

6. An apparatus for drilling wells comprising a source of power, a drilling implement, transmission mechanism between said source of power and said drilling implement including a friction driven element, with means engaging said drilling element for moving the same into and out of operative position responsive to a power increase demand beyond the normal demand. 115

120

7. An apparatus for drilling wells comprising a source of power, a drilling implement, transmission mechanism between said source of power and said drilling implement including a friction power transmitting element operable under abnormal conditions with means engaging said drilling implement for moving the same into and out of opera- 125

130

tive position responsive to a power increase demand beyond the normal demand, and means for disrupting connections in said engaging means.

8. An apparatus for drilling wells comprising a source of power and a drilling implement, means engaging said drilling implement for raising and lowering the same into and out of operative position, means directly responsive to and automatically governed in direct and reverse movement by a variable amount of power from the power source for raising and lowering said drilling implement, and means for disrupting connection between said forward and reverse power means and said engaging means.

In testimony whereof I have signed my name to this specification.

GEORGE D. PARKER.
